(57) **CLAIM**

The ornamental design for a baby foldable bottle warmer, as shown and described.

DESCRIPTION

FIG. 1 is a first perspective view of a baby foldable bottle warmer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the baby foldable bottle warmer thereof; and,

FIG. 10 is an enlarged view of the selected portion in FIG. 4.

The broken lines shown in the drawings depict portions of the baby foldable bottle warmer in which the design is embodied that form no part of the claimed design.
